UNITED STATES PATENT OFFICE.

WALLACE D. KELSEY, OF MINNEAPOLIS, MINNESOTA.

MARSH-SHOE.

SPECIFICATION forming part of Letters Patent No. 694,019, dated February 25, 1902.

Application filed November 2, 1900. Serial No. 35,247. (No model.)

To all whom it may concern:

Be it known that I, WALLACE D. KELSEY, a citizen of the United States, residing at Minneapolis, in the county of Hennepin and 5 State of Minnesota, have invented certain new and useful Improvements in Marsh-Shoes; and I do hereby declare the following to be a full, clear, and exact description of the invention, such as will enable others skilled in 10 the art to which it appertains to make and use the same.

My invention has for its object to provide an improved marsh-shoe adapted to be worn by draft-animals to enable them to travel 15 over marshes or boggy ground.

To the above ends my invention consists of the novel devices and combinations of devices hereinafter described, and defined in the claims.

20 The invention is illustrated in the accompanying drawings, wherein like characters indicate like parts throughout the several views.

Figure 1 is a plan view of a so-called 25 "marsh-shoe" constructed in accordance with my invention. Fig. 2 is bottom plan view of the same. Fig. 3 is vertical section on the line $x^3 x^3$ of Fig. 1, and Fig. 4 is a vertical section on the irregular line $x^4 x^4$ of 30 Fig. 1.

The sole-plate of the shoe is preferably made up of a flat metal plate 1 and a pliable plate 2, the latter of which may be constructed of an old rubber belting or any other suitable material and is projected at its margin 35 slightly beyond the margin of the metal plate 1. The two plates 1 and 2 are suitably secured together, as by rivets 3, and they are provided with perforations 4, which relieve 40 the shoe from suction while being lifted.

On the top of the sole-plate is adjustably and detachably secured a pair of side clamps 5, formed with beveled segmental flanges 6, which will approximately fit the sides of the 45 hoof of the draft-animal. The base-flanges of the side clamps 5 are provided with slots 7, and the metal plate 1 has vertically-projecting studs 8, which work through the said slots and are provided at their upper ends 50 with thumb-nuts 9.

One or more anchor-brads or sharpened studs 10 are rigidly secured to the metal plate

1 and project upward through the plate 2 just forward of the side clamps 5 and in the vicinity of the center thereof. A divided 55 toe-clamp made up of sections 11, pivoted to the flanges 6 of the side clamps 5, is arranged for engagement over the toe portion of the hoof. The upper ends of the clamping-sections 11 are adapted to be drawn together by 60 a bolt 12, passed through the said ends and provided with a thumb-nut 13. One of the said sections 11 is provided with a flange 14 at its free end, which engages the head of the bolt and prevents the same from turning. 65

To apply the shoe to a horse's hoof, the toe-clamping sections 11 are separated and the side clamps 5 6 are spread apart. The horse's hoof is then placed on the upper plate 2, with the toe portions of the hoof resting 70 upon the brads 10, which brads will be embedded in the hoof when the shoe is stepped upon. The side clamps 5 6 are then forced against the sides of the hoof and are secured by tightening up the thumb-nuts 9. Next 75 the sections of the toe-clamp are drawn together and tightly onto the forward toe portion of the hoof by means of the nut and bolt 12 13. Thus the shoe is securely fastened to the hoof. The hoof cannot be slid backward 80 from between the side clamps 5 6 for the reason that it is held against such sliding movement by the brads 10, and the hoof cannot be raised from the brads for the reason that it is held downward against the plate 2 by the 85 toe-clamp 11 and also by the flaring segmental flanges 6. It is, however, important to note that the shoe may be released from the horse's hoof by the manipulation of the nuts 9 and 13, all of which are located on the upper side of the sole-plate. Hence if the horse 90 should become mired in exceedingly soft or boggy ground a person reaching down through the hole made around the horse's leg by the sinking of the sole-plate could reach the said 95 nuts and release the horse's leg from the shoe.

Another important advantage should be noted—to wit, that the shoe may be applied to the unshod hoofs of the horse or draft-animal, thus saving the expense of having the 100 animal shod. As the pliable plate 2 projects at its margin beyond the margin of the plate 1 and beyond other portions of the shoe, especially the side portion, the liability of a

horse injuring his legs by contact with the shoes is avoided.

What I claim, and desire to secure by Letters Patent of the United States, is as follows:

- 5 1. A marsh-shoe comprising a sole-plate having laterally-spaced side clamps, a toe-clamp connected to said side clamps, and arranged to draw downward and rearward on the horse's hoof, and one or more brads projecting upward from said sole-plate, in position to engage the toe or forward portion of the horse's hoof and to prevent the same from sliding under the downward and rearward drawing action of said toe-clamp.
- 10 2. A marsh-shoe, comprising a sole-plate the side clamps 5 6 having slots 7, studs 8 pro-
- 15

jecting from said sole-plate through said slots 7, the nuts 9 on said studs 8, the two-part toe-clamp 11 pivoted to the flanges of said side clamps, the bolt 12 passed through the ends 20 of the clamping-sections 11 and provided with the nut 13, which nut 13 and which nuts 9 are removable from above the sole-plate, and one or more brads projecting upward from the forward central portion of said sole-plate, 25 substantially as described.

In testimony whereof I affix my signature in presence of two witnesses.

WALLACE D. KELSEY.
